Application February 14, 1946, Serial No. 647,639

5 Claims. (Cl. 232—1)

(Granted under the act of March 3, 1883, as
amended April 30, 1928; 370 O. G. 757)

1

The invention described herein, if patented, may be manufactured and used by or for the Government for governmental purposes, without the payment to me of any royalty thereon.

This invention is directed particularly to a retaining ring which forms part of the fixed structure for securing an ash tray and waste receptacle in a smoking stand in such a manner that it is rigidly secured therein but may be removed readily for cleaning the same.

Many different kinds of smoking stands and ash trays are now being made which include a compartment or receptacle communicating with the tray proper for receiving ashes, matches, butts, etc., from the tray. Some means for cleaning the receptacle or compartment must be provided in this type of smoking stand or ash tray, and in one form of smoking stand heretofore devised a removable waste receptacle in the form of a glass jar similar to a common Mason jar is provided which may be lifted from the stand, disconnected from the ash tray proper and emptied.

In this form of stand the ash tray proper is secured to a cap having threads for engaging threads on the neck of the jar, and it has a central opening communicating with the interior of the jar so that material deposited in the tray passes through the opening and into the jar. A flange around the rim of the tray proper engages along the edge of a well or aperture in the body of the smoking stand or in a separate housing attached to the stand. Thus the tray and jar are merely suspended in the stand and may be removed by lifting them out of the top of the stand. A disadvantage of this form of assembly is the fact that the tray and waste receptacle are not rigidly secured to the smoking stand. If the stand is accidentally tipped over there is nothing to prevent the ash tray and waste receptacle from sliding out of the well in the stand.

By the use of the retaining ring disclosed herein it is possible rigidly to secure the ash tray to the smoking stand and yet not interfere with the easy removal of the waste receptacle and the tray from the stand when it is desired to clean either or both. The ring is provided with a flange secured to the body of the stand concentric with the edge of the well therein and a second flange which is clamped between a bead at the base of the threaded neck of the jar and the cap when the latter is threaded onto the jar. Accordingly, it is an object of the invention to provide a new and improved means for rigidly securing an ash tray and waste receptacle in a smoking stand in

2

such a manner that they may be readily removed therefrom for cleaning.

Another object of the invention is the provision of a new and improved means for securing an ash tray and waste receptacle in a smoking stand which is durable in construction, readily secured in position when the stand is being assembled and which provides a rigid construction not easily damaged when subjected to hard usage.

A further object of the invention is the provision of a new and improved retaining ring for rigidly and removably securing a receptacle to a fixed support which may be rapidly stamped from sheet metal and easily mounted in position so that the cost of manufacture and assembly is reduced.

Other objects and advantages of the invention will become apparent from the following description and accompanying drawing in which Figure 1 is a side elevational view partly in section of a smoking stand incorporating the improved retaining ring described herein. Figure 2 is a perspective view of the ring; and Figure 3 is an enlarged fragmentary sectional view showing the manner of securing the waste receptacle in position on the stand.

In order to clearly disclose the invention it has been illustrated and will be described as incorporated in a specific type of smoking stand but it should be obvious that the invention can be adapted to a wide variety of stands and ash trays. Referring to the drawing the smoking stand shown in Figure 1 comprises a base 10, preferably 20 weighted, to which a vertically extending post 11 is secured by any suitable means.

Post 11 may be of any desired construction, but a preferred form is made from metallic tubing, square in cross-section, and shaped to a form 30 resembling an elongated C in general appearance. A square, circular or other shaped housing 12 is secured to the post adjacent its upper end by means of screws passing through a side wall of the housing and threaded into the post, 40 or by any other suitable means such as spot welding. An opening 13 in the top of housing 12 has an upturned edge 14 over which engages the beaded edge 15 of an ash tray 16 adapted to fit in the opening 13. A preferred form of ash tray 50 is shaped like an inverted cone and has a tapering bottom wall 17 with a central opening therein through which ashes and other waste pass into a receptacle 18 communicating with the opening in the bottom wall 17. A valve or gate 55 of known construction (not shown) may be pro-

vided in the opening in the bottom wall to prevent the escape of stale smoke or fumes from the receptacle when live cigar or cigarette butts are dropped into the ash tray.

Receptacles of various kinds may be used in smoking stands of this type, but glass jars, such as an ordinary Mason jar of pint size, have been found to be particularly suitable for this purpose because they can easily be replaced if they are accidentally broken. Such jars are provided with a neck having external threads upon which a metallic cap 19 is threaded and a bead or flange 20 at the base of the neck against which engages a lip 21 on the bottom edge of the cap 19. The top, of the cap, is of course removed to provide a passage and leaving, in effect, a threaded band provided with the lip or flange 21 on its lower edge. The cap is permanently secured to the underside of the bottom 17 of the tray and is concentric with the central opening therein. Thus the waste receptacle may be connected to or removed from the ash tray by screwing the jar 18 into the cap 19 or unscrewing it therefrom.

The construction just described could be used without further additions thereto, but in such a case the assembly would have to be supported in the stand by suspending it from the edge 14 of the opening 13, and there would be nothing to secure the assembly to the housing 12 so that it would very likely slide out of the opening 13 if the smoking stand were accidentally tipped over. To prevent this, I have provided a frusto-conically shaped retaining ring indicated generally by the numeral 22. This ring may be stamped from sheet metal such as a light steel. It is provided with an outwardly directed upper flange 23 having an inside diameter approximately equal to the diameter of opening 13 in the top wall of the housing. Tapering downwardly from this flange 23 is a side wall 24 which terminates in an inwardly directed flange 25. An opening 26 formed by the edges of the flange 25 is of sufficient size to pass over the neck of the jar 18, but the edges of the flange engage the bead 20 on the jar when the jar is inserted in position in the ring, as best seen in Figure 1.

In the finished smoking stand the retaining ring 22 is mounted in inverted position on the under side of the top wall of the housing 12 by means of screws 27 which pass through apertures 28 in the upper flange 23 and are threaded into the top of the housing 12, thus rigidly securing the ring to the housing. Obviously, the ring could be secured in position by welding. Lock washers 30 preferably are interposed between the screw head and the ring when screws are used to secure the ring.

An opening 29 in the bottom of the housing 12 must be provided for inserting and removing the receptacle 18. In assembling the smoking stand the tray 16 is placed in the opening 13 in the top of the housing 12, and the jar 18 is inserted into the housing through the opening 29 until the neck of the jar passes into the aperture 26 in the ring 22. While the tray is held in position with one hand the jar is threaded into the cap 19 with the other hand until the edges of the flange 25 are tightly gripped between the bead 20 on the jar and the lip 21 on the cap. It will be apparent that in this position the ash tray 16 and the receptacle 18 are rigidly secured in position, but may be removed when desired by unscrewing the jar from the cap.

In the preferred embodiment above described, both the ash tray 16 and receptacle 18 may be

removed from the stand. If desired the ash tray 16 may be rigidly and permanently anchored in the housing 12 by merely securing the lip 21 on the cap 19 to the edges of the flange 25 on the ring 22 by spot welding or other suitable means. Other modifications will become apparent to those skilled in the art, hence I do not desire to have my invention limited to the specific embodiment above described but desire to include 10 within the scope thereof all of the modifications defined by the appended claims.

I claim:

1. A smoking stand comprising a body portion provided with an opening, a downwardly extending frusto-conical ring mounted in said opening and secured to the wall thereof, an inwardly directed flange on the lower edge of said ring, an ash tray provided with an opening in its bottom and disposed within said ring, said ash tray being provided with screw threads on its lower end, a flange extending laterally from the lower edge of the ash tray and seated on said inwardly directed flange, a waste receptacle provided with an opening in its upper end, a laterally-extending flange spaced below the top of said waste receptacle, the upper end of the receptacle being threaded and engaged with the threads of the ash tray to thereby clamp the inwardly directed flange between the flanges on the ash tray and 30 waste receptacle.

2. A smoking stand comprising a body portion provided with an opening and an inwardly-directed flange having a free inner edge, a removable ash tray having a discharge opening in its bottom, a removable waste receptacle having an open upper end, and complementary attaching means on said ash tray and waste receptacle for detachably securing them together with the free edge of the inwardly-directed flange clamped between them.

3. A smoking stand comprising a body portion provided with a circular opening in its top wall, a downwardly-extending frusto-conical ring concentrically arranged with respect to said opening and secured to the wall of the opening, said ring having a free inner edge, a removable ash tray having a discharge opening in its bottom, a removable waste receptacle having an opening in its upper end, and complementary attaching means on said ash tray and waste receptacle for detachably securing them together with the free inner edge of the ring clamped therebetween.

4. A smoking stand comprising a body portion provided with an opening, a ring concentrically arranged with respect to said opening and secured to the wall of the opening, said ring having a free inner edge of lesser diameter than the opening, a removable ash tray having a discharge opening in its bottom, a removable waste receptacle having an opening in its upper end, the ash tray and the waste receptacle each provided with screw threads for detachably securing them together with the free inner edge of the ring clamped therebetween.

5. A smoking stand comprising a body portion provided with an opening, a ring concentrically arranged with respect to the opening and secured to the wall of the opening, said ring having a free inner edge, a removable ash tray having a discharge opening, an outwardly-directed annular flange on the ash tray and seated on the free inner edge of the ring, a waste receptacle provided with an opening in its upper end, an outwardly-directed flange on the waste receptacle, 70 and complementary attaching means on the ash

tray and waste receptacle for detachably securing them together with the free inner edge of the ring clamped between the outwardly-directed flanges of the tray and receptacle.
